CLAIM

The ornamental design for a table leg, as shown and described.

DESCRIPTION

FIG. 1 is a perspective view of a table leg, showing my new design, the broken lines being for environmental purposes only and forming no part of the claimed design;

FIG. 2 is a cross-sectional view of the table leg, taken along line 2—2; and,

FIG. 3 is a fragmentary bottom perspective view thereof.

FIG.1

FIG.3

FIG.2
